M. M. MARKS

LIGHTING FIXTURE

Filed Nov. 2, 1923

UNITED STATES PATENT OFFICE.

MYER M. MARKS, OF CHICAGO, ILLINOIS.

LIGHTING FIXTURE.

Application filed November 2, 1923. Serial No. 672,412.

To all whom it may concern:

Be it known that I, MYER M. MARKS, a citizen of the United States, residing at Chicago, in the county of Cook and State 5 of Illinois, have invented a certain new and

useful Improvement in Lighting Fixtures, of which the following is a specification.

My invention relates to shade holders, and the general object is to provide means which 10 may be readily and safely operated to secure the shade to the holder or to detach it. In a prior Patent 1,510,489 I have shown a shade holder having characteristics similar in some ways to those possessed by my pres-

15 ent device. I have shown in both cases a supporting element which is vertically slid- able upon the holder and passes downward to the inside of the shade; but in the earlier construction the vertically movable element

20 co-operates with stationary elements located on the opposite sides of the holder and adapted to engage the shade from the out- side thereof. Specifically, the stationary supporting elements are in the form of pins 25 which project radially inward from the holder and enter an annular channel formed in the upper rim of the shade. The result is that in that specific form the operator must see that the shade is held in engage-

30 ment with the pins while the movable sup- port is being slid downward to acting posi- tion. If during manipulation the shade leaves the pins it will drop. An object of my invention is to provide means which will 35 hold the shade in engagement with the holder on one side while the movable sup- porting element on the opposite side is being adjusted. This I accomplish, generally 40 speaking, by substituting for the pins of the previous construction a supporting ele- 45 ment capable of passing to the inside of the shade and confining the shade rim between it and the rim of the shade holder.

In the previous construction also it was 45 necessary, in order for the pins to function, to employ a shade whose upper rim was pro- vided with a channel into which the pins might enter. One of the objects of my pres- 50 ent invention is to provide a shade holder which may support shades having upper rims variously configurated and designed

with or without annular channels. Another object is to provide a support which will steady the shade while being adjusted and reduce any tendency for it to rock upon its 55 support.

As to previous construction, even where the shade had a channeled upper rim, the operation was not always reliable due to the fact that both shades and shade holders have 60 some irregularities due to exigencies of man- ufacture, and as the fixed pins were neces- sarily short the shade was not always prop- erly supported. With my new construction, in which both shade-supporting elements 65 pass to a considerable distance to the inside of the shade, the old difficulties are avoided.

I accomplish my objects by the mechanism illustrated in the accompanying drawings, in which—

Figure 1 is a vertical central section of my device showing it applied to a shade.

Figure 2 is a side elevation of the parts shown in Figure 1.

Figure 3 is a bottom plan view on a re- 75 duced scale showing the parts illustrated in Figure 1; and

Figure 4 is a sectional detail showing my device applied to a shade having a differ- 80 ent form of rim.

Like numerals denote like parts through- out the several views.

According to the illustrated design the body 1 of the shade holder is in the form of a canopy having slightly concave sides 85 terminating at the bottom in a vertical flange 2.

Located at opposite sides of the body are vertically extending slots 4 for accomodat- 90 ing the shanks of headed pins 6 and 7, which are secured at the inner ends to the shanks 8 of shade supporting elements 12. These support the shade 10 and are extended circumferentially for steadyng the shade when it rests upon them.

One of the pins, in this case the pin 6, is 95 extended upward so that it may be grasped by the operator for sliding the support up and down. While not essential it is desir- 100 able to form a hump or boss 14 in the body of the holder adjacent to the guide slots 4 for offering a slight resistance to the down-

ward movement of pin 6 when starting from the raised position. The purpose is to prevent the support from dropping down when brought to raised position shown in full lines at the right side of Figure 1. It makes the device more convenient to operate. It also prevents the support from being accidentally knocked upward to non-acting position, for example, when the device is being dusted.

It is also desirable but not essential to form a shoulder 15 in the body of the holder to form a stop against which a shoulder 16 in the shank of the support may engage to finally limit the downward movement of the support. However, this function may be performed by the lower pin 7 striking the lower end of the slot 4.

In Figure 1 I have shown a shade having the common form in which there is an annular channel 20 in the upper rim. My device, however, will operate upon shades in which the upper rim has other forms. In Figure 4, for example, the shade has an upper rim 22 which is approximately straight when viewed in cross section.

In operation, the operator may proceed in either of two ways, depending partly upon the form of shade to be used. If the channeled rim form, as shown in Figures 1 and 2, is to be employed he will first bring both of the supports 12 to retracted position as indicated in full lines at the right side of Figure 1. This will enable him to insert the rim between the flange 2 and the movable supports. He will then lower the supports to the position shown in full lines at the left of Figure 1 and in dotted lines to the right of Figure 1. In descending, the supports pass to the inside of the shade and when they are lowered they securely hold it in position in the holder. As pointed out in my prior application, if the device is mounted in a building where there is considerable vibration no harm will be done because the vibration, assisted by gravity, will have a tendency to lower the supports, which simply serve to maintain them in acting position. Thus there is no danger of the shades shaking loose.

If a shade whose upper rim is formed as shown in Figure 4 is to be used the operator may lower one of the supports 12 before he adjusts the shade to the holder. Then all he has to do is to lower the support on the opposite side. Consequently with such type of shade the support on one side may be lowered before the shade is brought to position, thus requiring the manipulation of lowering only one support after the shade has been positioned. Under certain conditions, especially if the operator is placing a shade above his head, it is not always convenient or possible for both of the supports to be lowered at the same time, but with my

device as soon as one of the supports has been lowered it will retain its side of the shade between it and the flange 2 of the holder as illustrated at the left of Figure 4. This reduces, if it does not actually prevent, the danger of the shade slipping out while the support on the opposite side is being lowered. This is an improvement over my prior type for with it the operator must see to it that the shade is held in engagement with the supporting pins while the movable element is being lowered into engagement.

Having thus described my invention, what I claim as new and desire to secure by Letters Patent is:

1. A shade holder flaring outward and downward in general and having a depending flange at the lower rim, the shade holder having slots arranged in vertical planes in the flaring portion, and independently movable shade supports having handles projecting out through the slots, said shade supports being slidably mounted upon the inner flaring surface and passing obliquely downward and outward a slight distance below the lower edge of the flange for retaining the shade rim within said flange and for passing to a point under the shade rim, said shade supports having circumferential extensions for steadyng the shade.

2. A shade holder of canopy form for shades which are open at the top and have an inward projecting rim at the opening in the top, said shade holder having a single pair of independently movable shade supports extending downward and outward through the upper opening of the shade for underlying the upper portion of the shade and supporting the shade, at least one of the shade supports being mounted on the inside of the shade holder and slidably obliquely downward and outward or upward and inward for engaging and disengaging the shade, there being but two of said shade supports located diametrically opposite to each other, and having peripheral extensions at the lower end for reducing the tendency of the shade to rock upon its supports.

3. A shade holder in the form of a canopy having vertically arranged slots on opposite sides, shade supports, projections on said supports passing outward through the slots for supporting and guiding them, the projections having heads outside of the canopy wider than the slots and the canopy having outpressed bosses for yieldingly engaging the projections and thus yieldingly holding the supports in raised, non-acting position, or in lowered, acting position.

4. A shade holder of canopy form for shades which are open at the top and have an inward projecting rim at the opening in the top, said shade holder having a station-

ary, depending flange at the lower periphery, and shade supports located within the shade holder, said supports extending obliquely downward and outward to a point inside of the shade holder at a sufficient elevation to hold the upper rim of the shade within said flange, at least one of said shade

supports being movable independently of the other and mounted on the inside of the shade holder and slideable obliquely downward and outward for engaging the shade. 10

In witness whereof, I have hereunto subscribed my name.

MYER M. MARKS.
